UNITED STATES PATENT OFFICE.

CHARLES W. GREEN, OF BROOKLYN, NEW YORK.

TOLL-GATE.

SPECIFICATION forming part of Letters Patent No. 362,954, dated May 17, 1887.

Application filed October 2, 1886. Serial No. 215,140. (No model.)

To all whom it may concern:

Be it known that I, CHARLES W. GREEN, of Brooklyn, in the county of Kings and State of New York, have invented certain Improvements in Toll-Gates, of which the following is a specification.

The object of this invention is to provide gates for use at ferries, railroad-stations, and other places where it is desirable that the passage of each individual may be under such conditions that the same may be noted or registered.

The said invention is more particularly designed to be used in connection with any suitable recording or registering devices—such, for example, as are very commonly employed with turnstiles; but the said invention is not limited to use in such connection.

Said invention comprises certain novel combinations of parts, whereby the opening of one gate or door is caused to be substantially simultaneous with the shutting of another, and vice versa, so that a person opening the one and passing through the gateway thereof will of necessity have to open the other, and the two being so arranged that but one person can pass at a time, such passage is capable of being distinctly noted, registered, or recorded, the said invention also embracing various novel combinations of parts, whereby motion may be transmitted from the one gate or door to the other with ease and certainty, and whereby the apparatus is made strong, effective, and durable.

Figure 1 is an elevation showing the construction and arrangement of the working parts of an apparatus embraced in my said invention. Fig. 2 is a vertical transverse sectional view taken in the line $x x y y$ of Fig. 1. Fig. 3 is a plan or top view of said apparatus, the top of the inclosing-frame being removed to show the parts. Fig. 4 is a horizontal sectional view taken in the line $w w$ of Fig. 1. Fig. 5 is a modification showing a cam-bar instead of an elbow-lever. Fig. 6 represents a modification in which ropes with weights are used for operating means instead of the elbow-lever. Fig. 7 represents an enlarged view of some of the parts shown in Fig. 1. Fig. 8 is a sectional view of the yoke shown in Fig. 7. Fig. 9 is a sectional view on line $x' x'$, Fig. 7. Figs. 10

and 11 represent enlarged views of the elbow-lever with anti-friction roller shown in Fig. 1. Figs. 12, 13, and 14 represent modifications, showing operative means for actuating the 55 sliding gate in unison with the hinged gate.

A is a gate or door, hinged at $a a$, and when opened or shut swinging on said hinges a .

B is a gate or door situated or arranged in suitable guides, B' , and sliding therein. 60

C is the passage-way. It is intended in practice that the passengers shall approach the passage C in the direction indicated by the arrow in Fig. 4, the gate B being pushed inward or back to leave open the passage C, as far as 65 concerns the gate B, while said passage is closed by the gate A. The passenger or person advancing passes from the passage C by pushing outward said gate A, which, as will hereinafter be explained, actuates the gate B 70 to slide outward to close the passage C behind the passenger or person as the gate A is opened, thereby preventing the entrance of another passenger or person until the gate A is returned to its place, and the gate B is thereby caused to slide back to its original position, whereupon another passenger or person may advance and actuate the gate A with the same operation upon the gate B, and so on *ad infinitum*. 75

When desired, the passenger or person may of course approach from the opposite direction, in which case the operation of the two gates will be reversed.

The normal position of the two gates is more 85 clearly shown in Fig. 4. The position of the gates in Figs. 1, 2, and 3 is the same as in Fig. 4. As represented in Figs. 1, 2, and 3, motion is transmitted from one gate to the other as follows: The sliding gate B is suspended from 90 horizontal track D by brackets b , which are preferably provided with anti-friction rollers c . (Shown in dotted outline.)

E is a lever, the upper end of which is pivoted, as shown at e , to the upper part of the 95 frame-work which surrounds the upper part of the apparatus, and the lower end of which is slotted, as shown at f . The lever E is arranged to swing in a plane parallel with the movement of the sliding gate B. A broad-headed bolt, g , is passed through the slot f and secured to the gate B, preferably near the 100

inner edge thereof, as shown in Fig. 1. The bolt *g*, instead of having a broad head, may be provided with a washer or key, as indicated at *a'* in Fig. 2.

It is of course to be understood that where the slotted lower end of the lever *E* works upon the bolt *g* in the operation of the sliding gate *B* said bolt *g* should be provided with an anti-friction roller to obviate the friction, 10 which might otherwise impair or hinder the operation of the said parts.

F is a swinging bar, pivoted, as shown at *i*, to the upper part of the gate-frame, and intended to move in substantially the same plane or in a 15 parallel plane with the lever *E*. The lower end of the swinging bar *F* is connected with the lever *E* by a horizontal link or bar, *G*. On this horizontal bar *G* is a stud or shoulder, *H*, the face *b'* of which is of sufficient length and width to receive the impact of the end of an elbow-lever, 20 *I*, which is attached at or near the top of the hinged gate *A*, at or near the inner edge thereof, in such a manner that when the gate is swung outward the outer or free end of the elbow-lever *I* will strike the shoulder *H*, and thereby move the same, together with the horizontal bar *G*, outward in the direction of the arrow shown in the upper part of Fig. 1, the said movement of the bar *G* swinging the lever *E* 25 in a corresponding direction, and the latter in turn sliding outward the gate *B* to close the passage *C* as the hinged gate *A* is swung open. To facilitate the operation of the elbow-lever *I* upon the shoulder *H*, the outer or free end 30 of the said elbow-lever should be provided with an anti-friction roller, *c'*.

J is a spring, one end of which is affixed to the gate-frame, and the other end of which is attached to the elbow-lever *I* in such a manner as to tend to retract the said elbow-lever in a direction the reverse of the arrow in said Fig. 1, thereby tending to shut the hinged gate *A* when the same is relieved from action in an outward direction. When desired, this 40 spring *J* may be replaced by or supplemented by a spring arranged to act directly upon the hinged gate *A* to tend to close the same, as indicated at *J'* in said Fig. 1, or by a "spring-hinge," commonly so termed, of sufficient 45 strength, arranged to tend to close the said hinged gate.

K is a spring, one end of which is affixed to the gate-frame *L*, and the other end of which is attached to the lever *E* in such manner as to tend to retract the said lever and to draw the sliding gate *B* back to its original position as the hinged gate *A* is closed. In order to avoid jar and concussion when the sliding gate *B* is thus brought back to its place, india-rubber buffers *f'* are arranged in the adjacent gate-post *L* in such a manner as to receive the impact of the inner edge of the said sliding gate *B* when the same is brought back to its place, as set forth. In order to avoid jar and 55 concussion of said gate *B*, and also to avoid liability of injuries to persons who may come in contact with it, the outer edge of said gate

B has attached to it a buffer, *i'*, composed of india-rubber tubing, placed parallel with and attached to the outer vertical edge of said gate 70 *B*, as represented more fully in Fig. 4.

It is of course to be understood that the elbow-lever *I* has its swinging end at such distance from the shoulder *H* when the hinged gate *A* is closed that the latter may be opened 75 to a considerable extent—as, for example, as shown in the dotted outline in Fig. 3—before the said elbow-lever begins to act upon the said shoulder *H*.

It will be further observed that by suitably 80 proportioning the length of the said elbow-lever *I* and the long and short arms of the lever *E* any desired ratio of speed between the movement of the sliding gate *B* and the movement of the hinged gate *A* may be obtained, 85 compensation being thus afforded for the stationary condition of the sliding gate *B* during the first part of the movement of the gate *A*.

M is an inverted horizontal ratchet, which 90 may be most conveniently supported by the horizontal bar *D*, and the shoulders of which are toward the outer edge of the sliding gate *B*. Attached to the latter, as more fully represented in Figs. 7 and 9, is a pawl, *N*, the office of which is to engage on occasion with the ratchet *M*. The pivot of this pawl is indicated at *g'* in Figs. 7 and 9, and from the inner end of the said pawl extends an upright arm, *N'*, at the upper extremity of which is a 100 yoke, *n*, the opposite ends of which constitute stops *n'*, as shown in the top detail view of Fig. 8.

R is an oscillating lever, the lower end of which is pivoted to the arm *N'*, as shown at 105 *e'*, (see Figs. 7 and 9,) and the upper end of which extends upward within the yoke *n*, and is preferably provided with an anti-friction roller, *m'*. A leaf-spring, *m*, is affixed to the sliding gate, and is curved, as shown at *r*, in 110 such a manner as to afford two inclined planes, *r'* and *r''*, which are so arranged that the action of the plane *r''* upon the upper end of the oscillating lever *R* will tend to move the same in one direction, while the action of the 115 other inclined plane, *r'*, will tend to move the said lever *R* in an opposite direction. The construction and arrangement of these parts are more fully represented in Figs. 7, 8, and 9, and the moving parts may be most conveniently attached to the sliding gate *B* by means of the two supporting-plates *S S*, as shown in 120 Figs. 7 and 9.

T is a stop, (shown in Figs. 1 and 3,) in contact with which the lever *R* is brought toward the completion of the outward movement of the sliding gate *B*. The normal position of the parts is such that when the said sliding gate *B* is moved inward to close the passage *C*, as hereinbefore explained, the pawl *N* will 125 remain in gear with the ratchet *M*, so that if any attempt to reverse the movement of the gate *B* be made by force applied thereto such 130 movement will be resisted by the ratchet and

the pawl. When the hinged gate A is suffered to return to its closed position, as hereinbefore explained, the reverse movement of the elbow-lever I brings the latter against the oscillating lever R until the same is brought from the inclined plane n'' to the inclined plane r'' of the leaf-spring m, the end of the oscillating lever R being thereby brought against the adjacent shoulder n' of the yoke n, whereupon the backward movement just mentioned of the oscillating lever R is communicated to the arm N' of the pawl N, thereby bringing said pawl out of contact with the ratchet M, thereby disengaging the sliding gate B from its connection with the ratchet and permitting the reverse movement of the said sliding gate B consequent upon the closing of the hinged gate A, hereinbefore explained. As the sliding gate approaches the end of its reverse movement aforesaid, the stop T strikes the adjacent side of the oscillating lever R and forces the same back to its position in which it is acted upon by the inclined plane n'' , whereupon, the said lever R coming in contact with the other or opposite shoulder, n' , the arm N' is correspondingly tilted and the pawl N is again brought into gear or connection with the ratchet M. The coincident movement of the hinged gate A and the sliding gate B may be registered by any suitable registering apparatus, to which movement is communicated from one or the other, or both, of the said gates, as represented in Fig. 1.

The registering apparatus may be actuated by mechanism as follows: A horizontal rod, A⁵, has one end pivoted to the lower arm of an elbow-lever, B⁵, which is supported by the adjacent gate-post C', or otherwise. The opposite end of the rod A⁵ is supported in a suitably-fixed guide, C⁵, and is so arranged that during the closing movement of the gate B the lever E will strike the rod A⁵, and thereby actuate the elbow-lever B⁵, so that the latter, through the rod D⁵, may give motion to a crank, F⁵, which in its turn may be connected, by any suitable mechanism, with a bell or other suitable signal device, and also with any suitable recording apparatus; but as neither such signaling nor such recording device forms in itself any portion of this invention, the same has been omitted from the drawings.

When desired, the modified apparatus represented in the plan view in Fig. 5 may be employed for transmitting motion from the swinging gate A to the sliding gate B. In this a horizontal lever, A', works on a vertical pivot, a⁴. One arm, b⁴, of this lever A' is so arranged as to be acted upon by the gate A when the latter is swung open, the gate A being preferably provided with an anti-friction roller, c⁴, to provide a buffer for the arm b⁴ of the said lever. The other arm, d⁴, of the said lever A' is curved to constitute, in effect, a cam, which acts upon a stud or anti-friction roller, e⁴, on the top of the sliding gate B. When the arm b⁴ is swung outward by the opening movement of the hinged gate A, the

cam-like action of the arm d⁴ moves inward the sliding gate B. When the arm b⁴ is relieved by the release of the gate A, the lever A' is permitted to resume its original position, the sliding gate B being retracted by the spring J, and the stud or anti-friction roller e⁴ acting upon the arm d⁴ to return the lever A' to its place.

When desired, movement from the swinging gate A to the sliding gate B may be transmitted by the modification of the apparatus shown in the elevation in Fig. 6. In this there extends from the swinging edge of the hinged gate A over a pulley, g⁴, attached to the adjacent gate-post C', a cord, B', which is connected, by link h⁴ or otherwise, to the lever E, from which, over a pulley, m⁴, attached to the adjacent gate-post L, is another cord, A⁴, to which is attached a weight, n⁴. The lever E is connected with the sliding gate B in substantially the same manner as represented in Fig. 1. The outward or opening movement of the gate A draws upon the cord B', and thereby actuates the lever E to move the sliding gate B in due relation with the gate A. When the gate A is released, both of the gates A and B, together with the lever E, are drawn back to their original position by the weight n⁴ acting through the cords B' and A⁴. When desired, the movement may be transmitted from the hinged gate A to the sliding gate B by the modified mechanism illustrated in Fig. 12, which is also a plan view. In this the gate A is provided with an arm, D', which, when the gate A is swung open, acts upon the radial arm E' of a toothed sector, F', which gears into a pinion, G', the pinion and the sector having suitable journals, r⁴ and s⁴, supported on the fixed upper part of the gate-frame. The pinion G' gears into a straight rack, H', attached to the top of the sliding gate B. The spring J is arranged in relation with the sliding gate B in substantially the same manner as shown in Figs. 1 and 5, and for the same purposes. When the gate A is swung open, motion is transmitted through the sector, pinion, and rack to slide inward or close the gate B. When the gate A is released, the spring J retracts the gate A to its original position, and transmitting motion through the rack, pinion, and sector aforesaid, closes the gate A. In the modification shown in plan in Fig. 13 provision is made for two separate passages C and two swinging gates A, each hinged as shown at a, and which are, in fact, duplicates of the swinging gate shown in the other figures, as hereinbefore set forth. The single sliding gate B is used, and to the top of this is attached the rack H', as shown in Fig. 12. Into this rack H' gears a sector, J', which works on a vertical shaft or pivot, t', direct to which, or to the sector, are attached two levers, K' and K'', one of which bears against an anti-friction roller, a⁵, on the outer edge of the left-hand hinged gate A, and the other of which bears against another anti-friction roller (also indicated by the reference-letter a⁵)

at the outer edge of the other or right-hand gate A. When the right-hand gate A is swung outward, it acts upon the lever K', and thereby actuates, through the sector J⁴ and rack H', the gate B to move the latter behind the person who opens the gate A aforesaid, and thereby closes the passage C behind said person. Each gate A should be provided with a spring hinge, or with a geared or pulley arrangement, which will close the same when relieved from the outward pressure exerted in opening it, so that each gate, after being opened, will return independently to its closed position. When the other—as, for example, the left-hand—gate (indicated in Fig. 13) is moved outward, it acts upon the lever K', and thereby causes the gate B to slide outward behind the person opening the said gate in the same manner and for the same purpose that it had previously moved with reference to the other of the said gates A. In order that the left-hand one of the gates A shall not be opened until the right-hand gate is closed, provision is made for locking the gates alternately, as follows:

Two latches, B⁴, are hinged adjacent to the gate-posts L and C', and are connected by a horizontal bar, C', the ends of which are pivoted to the said latches. Each of said latches is provided with the latching-shoulders e⁵ and with an inclined shoulder, d⁵. The latches B⁴ work on vertical pivots e⁵, and the said latches are themselves horizontal.

Projecting upward from the top of each gate is the stud f⁵. When the left-hand gate A is closed, its stud f⁵ strikes the incline d⁵, and thereby swings the latch B⁴ until its latching-shoulder e⁵ passes over the stud f⁵, and thereby prevents the opening or swinging movement of the adjacent gate A. The movement just described of the one latch B⁴ is transmitted through the bar C' to the other latch B⁴, and tilts the latter outward and away from the position of the studs f⁵ of the other gate, thereby permitting the latter to be swung open. The operation of the said other gate in relation with the adjacent latch B⁴ and its adjuncts is of course simply a repetition of that just described.

In the modification represented in the elevation represented in Fig. 14 a cord, D⁴, extends from the free or swinging end of the gate A over a pulley, g⁴, as more fully represented in Fig. 6, and thence passes through a hole or slot in a bracket, g⁵, which is attached to the sliding gate B, thence over the pulley m⁴, secured to the side post, L, and has attached to its extremity a weight, n⁴. The cord D⁴ has secured to it a stop, h⁵, which is arranged behind the bracket g⁵. From the bracket g⁵ extends a cord, i⁵, over a pulley, j⁵, secured to the upper cross-bar of the frame-work of the apparatus, and it has at its lower end a weight, k⁵. When the gate A is swung open, it draws upon the cord D⁴, and through the stop h⁵ and the bracket g⁵ draws inward the sliding gate B. When the gate A is relieved from pressure in its opening or outward movement, it is

closed by the action of the weight n⁴ exerted through the cord D⁴, simultaneous with which the sliding gate B is drawn back to its original position by the weight k⁵ acting through the cord i⁵.

The gates A and B may be of any suitable construction and of any required width or height. When desired, they may be composed partly of wire-netting, as illustrated in Fig. 1, in order to permit a clear view through the said gates when in their closed position.

It is of course to be understood that the passage C, in which the sliding gate B moves, and the place occupied by the hinged gate A when the same is closed, should be of such length or size as may be required by the passenger in operating the apparatus, as hereinbefore explained.

What I claim as my invention is—

1. The combination of a hinged gate and a sliding gate with a lever actuated by the hinged gate and mechanism, substantially as described, connected to the sliding gate, whereby the action of the hinged gate in either direction actuates the sliding gate in the opposite direction, all substantially as described.

2. The combination, with the hinged gate A and the sliding gate B, of an elbow-lever, I, lever E, horizontal bar G, having a stud or shoulder, H, and means for supporting the end of the said bar G opposite that attached to the lever E, substantially as and for the purpose herein set forth.

3. The combination, with the hinged gate A and the sliding gate B, of an elbow-lever, I, lever E, horizontal bar G, having shoulder H and means for supporting the end of the said bar G opposite that attached to the lever E, and spring J, substantially as and for the purpose herein set forth.

4. The combination, with the hinged gate A and the sliding gate B, of an elbow-lever, I, lever E, horizontal bar G, having a stud or shoulder, H, and means for supporting the end of the said bar G opposite that attached to the lever E, and spring K, substantially as and for the purpose herein set forth.

5. The combination, with the hinged gate A and the sliding gate B, of an elbow-lever, I, lever E, horizontal bar G, having shoulder H and means for supporting the end of the said bar G opposite that attached to the lever E, and springs J and K, substantially as and for the purpose herein set forth.

6. The combination, with the hinged gate A and the sliding gate B, of an elbow-lever, I, lever E, horizontal bar G, having shoulder H, and swinging lever or bar F, substantially as and for the purpose herein set forth.

7. The combination, with the hinged gate A and the sliding gate B, of an elbow-lever, I, lever E, horizontal bar G, having shoulder H, swinging lever or bar F, and spring J, substantially as, and for the purpose herein set forth.

8. The combination, with the hinged gate A and the sliding gate B, of an elbow-lever, I,

- lever E, horizontal bar G, having shoulder H, swinging lever or bar F, and spring K, substantially as and for the purpose herein set forth.
- 5 9. The combination, with the hinged gate A and the sliding gate B, of an elbow-lever, I, lever E, horizontal bar G, having shoulder H, swinging lever or bar F, and springs J and K, substantially as and for the purpose herein set forth.
- 10 10. The combination, with the hinged gate A and the sliding gate B, of a lever attached to said gate A, mechanism, substantially as described, connected to said gate B, for imparting motion to said gate B in an opposite direction from that of gate A, the ratchet M, the pawl N, and means, substantially as described, connected to said pawl, for engaging the said pawl with and disengaging the said pawl from said ratchet, as described, all as set forth.
- 15 11. The combination, with the hinged gate A and the sliding gate B, of the ratchet M and pawl N, having the oscillating lever R, yoke n, shoulders n', leaf-spring m, having the inclined planes r'' and n'', and means, substantially as described, for actuating the oscillating lever R in unison with the movement of
- the sliding gate B, all substantially as and for the purpose herein set forth.
12. The combination, with the hinged gate A and the sliding gate B, of the ratchet M and pawl N, having the oscillating lever R, yoke n, shoulders n', leaf-spring m, having the inclined planes r'' and n'', and elbow-lever I, attached to the hinged gate A, all substantially as and for the purpose herein set forth.
13. The combination, with the hinged gate A and the sliding gate B, of the ratchet M and pawl N, having the oscillating lever R, yoke n, shoulders n', leaf-spring m, having the inclined planes r'' and n'', and elbow-lever I, attached to the hinged gate A, and stop T, all substantially as and for the purpose herein set forth.
14. A toll-gate having a hinged gate and a horizontal sliding gate, and provided with a lever adapted to be actuated by the movement of the hinged gate in either direction, and thereby actuate the sliding gate in an opposite direction, substantially as set forth.

CHARLES W. GREEN.
